HANDCUFF, LEG IRON, SHACKLE
AND THE LIKE

Samuel P. Gray, Forest Hills, N. Y.

Application May 17, 1950, Serial No. 162,414

7 Claims. (Cl. 70—16)

1

The present invention relates to handcuffs, leg irons, shackles and the like, of the type used by the military and the police.

The principal object of this invention is to provide articles of the character mentioned, of novel and improved construction, which if attempted to be "picked," will suffer continuous reduction in cuff size and made successful "picking" impossible because cuff size would need be made considerably smaller than the limb under shackle, in most compressed condition humanly bearable.

A further object of this invention is to provide novel and improved items of the nature set forth, which are reasonably cheap to manufacture, easy to use and efficient in carrying out the purposes and functions for which they are designed.

Other objects and advantages will become apparent as this disclosure proceeds.

In the accompanying drawings forming part of this specification, similar characters of reference indicate corresponding parts in all the views.

Fig. 1 is a front view of an open handcuff or the like, embodying the teachings of this invention. A front member is omitted from this view in order to expose the lock mechanism housed in a space afforded by a spacer member between said front and a similar back member. The lock mechanism includes detents of various constructions for cooperation with a movable ratchet which is part of the cuff, and also means to lock various of the detents in ratchet-engagement position.

Fig. 2 is a similar view showing the cuff in closed condition.

Fig. 3 is a side view of Fig. 1, fully assembled.

Fig. 4 shows one of said detents and its key-operated locking means, in position as they are in the assembly.

Fig. 5 shows another detent as it is associated with said detent-locking device. Figs. 4 and 5 are front views.

Fig. 6 is a perspective view of still another detent included in this device.

Fig. 7 is a perspective view of a key for operating the components of the locking mechanism to assume locked and unlocked condition.

Fig. 8 is a perspective view of the spacer member mentioned.

Fig. 9 is a fragmentary section taken at lines 9—9 in Fig. 1.

In the drawings, the illustrated embodiment is of the type including a pair of substantially identical flat plate members 14 and 16, assembled with a flat U-shaped spacer 17 between them, by

2

means of rivets 18 or in any other suitable manner. This structure affords an open-top chamber 19 for housing the lock mechanism. Each of said plates extend above the top of said chamber and has an integral band, preferably arcuate in shape, extending from one side of the chamber 19, whereby the concave edge of such band is nearest to said chamber. These extending arcuate bands indicated respectively by the numerals 15' and 16', are identical. Between them, at their free ends on a pin 20, is pivotally mounted a flat arcuate band 21, at an end of the latter so that said band 21 is free to be rotated between said bands 15' and 16'. The top edges of the arms 17' and 17" of the U-shaped spacer member 17, and a substantial portion of the convex surface of the band 21, commencing from the free end of said band 21, lie along the perimeter of a circle whose center is the axis of the pin 20, or nearly so as possible, so that the ratchet teeth denoted generally by the numeral 22 along the mentioned convex edge portion of the band 21, shall be in sliding contact with such top edges of the arms of said spacer 17, upon rotation of the band 21 about axis pin 20. The bands 15', 16' and 21 form a ring or cuff to shackle a limb of a prisoner, in which position of the bands, the toothed portion of band 21 spans the arms of the spacer 17 and closes the top of the chamber 19. However, quite a number of said teeth 22 remain exposed to enable adjustment to a smaller cuff size of prescribed limit. The thickness of the ratchet band 21 is precisely as possible the distance between the plates 15 and 16. It is to be noted that when the cuff is closed, said ratchet band 21 lies between said plates above the chamber 19.

The floor of chamber 19 is preferably flat, along which a bolt 23 may slide. This bolt is for locking in place, the detent 26 which engages the ratchet band 21; said detent being swingably mounted on a fixed pin 27, and maintained in such engagement by the blade spring 28. This spring, constantly under stress, is of U form, whose bight is positioned about the fixed pin 29, so that one arm thereof acts against the detent 26, and its other arm provided with an arcuate bend 28', sets pressingly in one of the notches 23' or 23" in the top edge of the bolt member 23. A fixed pin 30 suited for the socket 31' of the hollow-barrel key 31 shown, is fixed in plate 16 and extends to the plane of the outer surface of plate 15, through a suitable keyhole, not shown. It is desirable and known practice to make the detent 26 and the bolt 23 of several thin flat

plates, in contact, but free of each other rather than in one thick piece, in order to minimize "picking" possibility. The bolt 23 is provided with the notch 23'', while the detent 26 has a notch-like form at 26'', in which mentioned notches, the key tooth 31'' may respectively engage to either shift the bolt 23, or swing the detent 26. The spacer member 17, in an exposed portion thereof, may have a hole 24, for a short stout chain 25 to join a pair of such handcuff devices.

The structure thus far specifically described in detail, is well known in the art and its operation and use is common knowledge. To shackle a limb of a prisoner, requires no key. The cuff is maintained against opening, once it is closed about a limb, by engagement of the detent 26 with the ratchet band 21. Of course, ratchet band movement is free to decrease cuff size, unless the key is used to shift the bolt 23, so that tooth 33 prevents detent movement at tooth 34.

In police and military experience, opportunity is not always available to accomplish double locking by the use of the key 31 to secure the detent 26 against movement. Reliance is had therefore solely on the engagement of the single detent 26, whether of one or more pieces, and the ratchet band 21, for locking the shackle in most instances. Security is rather speculative, because some deviation from precise fit, and such does occur, has permitted insertion of picking wires to swing the detent 26 out of engagement from the ratchet band 21, with some, but not prohibitive discomfiture to the prisoner. In this regard, consider that the locking mechanism comprises only the detent 26, the ratchet band 21 and the spring 28 effecting their engagement as in Fig. 2. Assume that the picking wire could be inserted from the right in Fig. 2, between the arm 17' of the spacer member 17, and the teeth 22 of the ratchet band 21, and thence into the chamber 19 until the end of said wire contacts the corner 35 in detent 26. Such wire, not shown, could then be made to enter upwardly between the teeth 36 and 37, and if stiff enough, such wire could then force disassociation of said detent and ratchet means, and the cuff thus opened. Space for such wire between said two teeth 36 and 37 is easily afforded by a slight squeeze on the cuff parts 15', 16' and 21 towards one another for movement of the ratchet band 21 of less than the pitch of said teeth.

Then again, if picking is attempted from the left in Fig. 2, assume that the picking wire could be passed between arm 17' of the spacer member 17 and the teeth 22 of the ratchet band 21, and thence into the chamber 19 until the end of the wire enters between the teeth 38 and 39, and if stiff enough such wire could force disassociation of the detent member 26 from the ratchet band 21, and the cuff be thus opened. At most, in such operation, the cuff will be closed by another two teeth to effect this picking, which will not unduly harm the limb or cause the prisoner unbearable pain.

In the practice of this invention, I employ two additional detent means, specially positioned with respect to detent 26, and cooperating in a manner as will be explained. These are denoted generally by the numerals 40 and 41 respectively.

Detent 40 has a tooth 42 for engagement with the ratchet band 21 in teeth of the latter which have passed beyond the teeth of detent 26 when the cuff is set in closed condition, while detent 41 has a tooth 41' for engagement of the ratchet band 21 in the teeth thereof which have not as

yet come in contact with those of detent 26 during the setting of the cuff in closed condition. Detent 40, swingably mounted on pin 27, is similar in body construction to the detent 26, to permit its downward swing by operation of the key 31, and its locking by the bolt 23.

Detent 41 may be a latch slideable in slot 44, longitudinally in arm 17' of the spacer member 17, and urged into engagement with the ratchet band 21 by means of a stressed compression coil spring 45. This detent 41 has a pair of projecting elements 46 and 47, spaced longitudinally thereon, between which is the finger 48 extending from the detent 40 which lies in cut-out 49. The position of this finger between said elements 46 and 47 is such, that the detent 41 can be shifted out of engagement with the ratchet band 21, without either of said elements movingly touching the finger 48, and the detent 40 can be moved out of engagement with said ratchet band 21, without said finger movingly touching said elements 46 or 47. But dimensions are such that when detent 40 is swung by the key movement, such shifting of said detent 40 is sufficient so that its finger 48 contacts element 47 and shifts detent 41 out of engagement with said ratchet band. When the cuff is closed, all three detents 41, 26 and 40 will engage the ratchet band 21.

Let us now consider "picking" this locking mechanism. Assume that a picking wire could be inserted from the right in Fig. 2, between the arm 17' of the spacer member 17, and the teeth 22 of the ratchet band 21, and thence into the chamber 19 until the end of the said wire contacts the side 50 of tooth 42 of detent 40. Even if said wire would go up between the teeth 42 and 51, if it were not stopped by edge 50 of tooth 42, said wire of necessity will become bent and even if it could be pushed to the teeth of the detent 26, such bent end of the picking wire could do nothing further to open detent 41. Then again, if "picking" is attempted from the left in Fig. 2, the picking wire say can be inserted at 53 and the cuff closed a bit more so that said wire contacts the straight edge 41'' of the detent or latch 41, such wire will become bent, and say it does not bend, but actually pushes the detent 41 out of engagement with the ratchet band 21, the cuff size has thus become smaller by at least two teeth of 22. As the wire is pushed further, cuff size becomes smaller, and by the time the teeth of detent 26 are disengaged, cuff size has suffered another decrease of several teeth in size. Then to overcome the engagement of detent 40, another decrease in cuff size must occur. The total resulting necessary decrease in cuff size is so great that the shackled limb would be crushed to be contracted to such resulting reduced cuff size. So though picking of the lock mechanism may be theoretically possible, the shackled limb would have to be of sponge rubber nature, to be accomplished. It might be noted that if picking were attempted, the picking wire would be stopped by the straight edge 41'' or 50 respectively, so that even attempts made with a wire inserted at each end of the chamber 19, would prove futile. The stiffness of springs 28 and 45, the precision fit of the parts, and the limited dimension between plates 15 and 16, besides the constructional incidents and relative positions of the three detents, would require much a stronger wire than is possible here for use.

It may here be noted that the detents 40 and 41 may be or several separate thin plates or pieces free of each other, as mentioned for the

detent member 26, in order to avoid successful picking by a thin blade inserted between the ratchet member 21 and one of the plates 15 or 16 on which are mounted the locking mechanism. For if one of the pieces composing a detent member were disengaged from the ratchet member, the remainder would continue in engagement and the shackle remain closed.

Also to be noted, that but a single spring 28 acts to maintain both detent members 26 and 40 in engagement with the ratchet member 21, and although detent 26 becomes disengaged, the lessening of the angle between the arms of said spring would not be sufficient to release detent member 40 from its engagement from the ratchet member 21, because of the greater angle of swing required of detent member 40 to accomplish its release. Any other spring means would need be further stressed after release of detent member 26, to afford release of detent member 40, if such spring acts between the axis of swing of such detent members and the points on the ratchet member where such detent members respectively engage such ratchet member. Use of a single spring in the instance mentioned, not only makes for economy in assembly, but gives a stronger spring for both detent members 26 and 40, than would be possible if a separate spring were used for each. Also, bulkiness is avoided.

This invention is capable of numerous forms and various applications without departing from the essential features herein disclosed. It is therefore intended and desired that the embodiment shown herein be deemed illustrative and not restrictive and that the patent shall cover all patentable novelty herein set forth; reference being had to the following claims rather than to the specific description herein to indicate the scope of this invention.

I claim:

1. A handcuff, shackle or the like, including a ratchet member constituting part of a cuff, a lock-mounting member constituting the other part of the cuff; both said members being pivotally connected so that when one is moved with respect to the other, the size of the cuff is changed or the cuff is opened for the admission of a limb to be shackled thereby; the teeth of the ratchet member being arranged at its free end along an arc whose center is said pivot point, and lock mechanism carried on said mounting member, including two spring-loaded detent members adapted to engage the ratchet teeth when the cuff is closed, permitting free movement of the ratchet member to reduce cuff size and preventing movement of said ratchet member to increase cuff size; said two detent members being positioned so that one of them engages the ratchet member before the other does, upon movement of the ratchet member to close and reduce the size of the cuff, means on a particular one of said detent members, adapted to cooperate with a key whereby upon key movement in a given direction, said particular detent member is moved out of engagement from the ratchet member and cooperating means on both said detent members permitting each of said detent members independent movement for disengagement from the ratchet member without effecting one another except that upon movement of said particular detent member further away from the ratchet member by further operation of the key after said particular detent member is disengaged from said ratchet member, such cooperating means on the detent members will coact to

move the second detent member out of engagement from the ratchet member, whereupon the said ratchet member is released for movement in both directions about the pivot point.

5 2. A device as defined in claim 1, wherein the two detent members are so positioned that when they both are in engagement with the ratchet member there is at least one unengaged tooth of said ratchet member between said detent members.

10 3. A device as defined in claim 1, wherein the mentioned cooperating means on the two detent members comprises two spaced elements on one of said detent members and a third element extending from the other of said detent members into the space between said first two elements whereby on movement of either of the detent members back and forth, said third element will be in contact with each of the other elements respectively a predetermined period.

15 4. A device as defined in claim 1, wherein one of the detent members is swingably mounted and the other is slidably mounted on the mounting member.

20 5. A device as defined in claim 1, wherein the lock mechanism includes a third detent member which is spring-loaded and positioned to engage the ratchet member between the points of engagement of the other two detent members with the ratchet member; said third detent member having means adapted to cooperate with the key whereby upon movement of the key to cause release of the first two detent members from engagement with the ratchet member, the said third detent member is also released from such engagement with the ratchet member; said third detent member being so positioned that when all three detent members are in engagement with the ratchet member, there is at last one unengaged tooth of the ratchet member between every two detent members.

25 6. A device as defined in claim 5, wherein the said third detent member and one of the others are each swingably mounted and acted on by a single spring positioned to contact them at points between their axes of swing and the points where they respectively engage the ratchet member, whereupon disengagement of one such detent member from the ratchet member, the other detent member will remain in engagement with said ratchet member.

30 7. A handcuff, shackle or the like, including a ratchet member constituting part of the cuff, a lock-mounting member constituting the other part of the cuff; both said members being pivotally connected so that when one is moved with respect to the other, the size of the cuff is changed or the cuff is opened for the admission of a limb to be shackled thereby; the teeth of the ratchet member being arranged at its free end along an arc whose center is said pivot point, and lock mechanism carried on said mounting member, including two spring-loaded detent members 35 adapted to engage the ratchet teeth when the cuff is closed, permitting free movement of the ratchet member to reduce cuff size and preventing movement of said ratchet member to increase cuff size; said two detent members, being individually movable in the same direction to disengage the ratchet member, and said two detent members being positioned so that one of them engages the ratchet member before the other does, upon movement of the ratchet member to close and reduce the size of the cuff, and when they both are in

engagement with the ratchet member, there is at least one unengaged tooth of said ratchet member between said detent members.
